UNITED STATES PATENT OFFICE.

ANTHONY DIXON BROGAN AND ANDREW MURRAY MALLOCH, OF FIRHILL,
GLASGOW, COUNTY OF LANARK, SCOTLAND.

DESIGN FOR THE SURFACE ORNAMENTATION OF GLASS.

SPECIFICATION forming part of Design No. 18,893, dated February 5, 1889.

Application filed November 23, 1888. Serial No. 291,632. Term of patent 14 years.

To all whom it may concern:

Be it known that we, ANTHONY DIXON BROGAN and ANDREW MURRAY MALLOCH, citizens of the United Kingdom of Great Britain and Ireland, residing at Firhill, Glasgow, in the county of Lanark, Scotland, have invented a new and original Design for the Surface Ornamentation of Glass, of which the following is a specification, reference being had to the accompanying drawings, forming part thereof, in which—

Figure I is a face view of our design; and Fig. II is a section on the line II II, Fig. I.

The design is for the surface ornamentation of glass; and, as represented in the drawings, it consists of a series of panels, squares, or quadrilateral figures on a body or backing, 1, whose boundaries are coterminous and each of which is composed of alternating ridged and grooved lines or corrugations, the lines of

corrugations in each figure 2 running at right angles to those in the adjoining figures, 3, the figures being arranged on longitudinal and transverse cross-lines similar to the figures on a chess-board. In the drawings the ridges are represented by black lines, the white spaces corresponding to the grooves.

We claim—

The design for the surface ornamentation of glass, substantially as herein shown and described.

In witness whereof we have hereunto set our hands this 2d day of October, 1888.

A. D. BROGAN.
A. M. MALLOCH.
